WINDOW STRUCTURE

Otto H. Merz, Wauwatosa, Wis.

Application February 28, 1942, Serial No. 432,771

2 Claims. (Cl. 20—52.6)

The present invention relates generally to improvements in the art of building, and relates more particularly to improvements in the construction and operation of window structure of the sliding sash type.

An object of the invention is to provide an improved window assemblage which is simple and durable in construction, and which is also highly efficient in use.

It has heretofore been common practice in the building industry, to utilize multiple sash windows provided with weather strips, and in which the sash sections are separated by horizontal check rails and are vertically slidable relative to each other. The weather strips for sealing these prior windows against infiltration of cold air and escape of heated air from the interior, as well as for preventing rattling, were ordinarily formed of long strips of special resilient metal which has become extremely difficult to obtain. Due to the fact that the sash sections of these prior windows were vertically slidable or adjustable, it also required the provision of either weights, pulleys and cords, or spring sash balances, both embodying metal parts and involving considerable complication, in order to automatically retain the sash in various positions of adjustment. The provision of these metal parts and mechanisms in prior window assemblages of the sliding sash type, made it rather difficult to construct and to assemble the structures, and considerably increased the cost of manufacture, installation, and maintenance thereof.

It is therefore a more specific object of my present invention to provide an improved sliding sash window assembly wherein the sash sections may be readily adjusted and retained in adjusted position without the aid of weights or spring sash balances, and which is tightly sealed without utilizing metallic or other costly weather stripping.

Another specific object of the present invention is to provide a new and useful window structure having two or more relatively slidable sash members separated by one or more upright check rails, and wherein the sash guides and check rail are utilized to tightly seal the window when closed.

A further specific object of this invention is to provide an improved window of the sliding sash type wherein the sash sections are relatively horizontally slidable to provide ventilating and access openings of maximum height, and which can be manufactured, installed and maintained at minimum cost.

Still another specific object of the invention is

to provide an improved window assemblage most of the parts of which may be constructed of non-metallic materials, which is strong and durable in structure, and which is moreover extremely effective in operation.

These and other objects and advantages of the present invention will be apparent from the following detailed description.

A clear conception of the various features constituting the present improvement, and of the mode of constructing and of utilizing window structures embodying the invention, may be had by referring to the drawings accompanying and forming a part of this specification wherein like reference characters designate the same or similar parts in the several views.

Fig. 1 is an outside elevation of a typical two sash window embodying the invention, the window being closed and portions having been broken away to reveal normally concealed structure;

Fig. 2 is an enlarged transverse vertical section through the lower part of the window of Fig. 1;

Fig. 3 is a similarly enlarged transverse vertical section through the upper part of the same window;

Fig. 4 is a likewise enlarged horizontal transverse section through one side of the two sash window;

Fig. 5 is a similar section through the opposite side of the same window assemblage;

Fig. 6 is a transverse similarly enlarged horizontal section through the upright check rail between the two sash;

Fig. 7 is an outside elevation through a modified three sash window assembly also embodying the present invention; and

Fig. 8 is a fragmentary somewhat enlarged section through the window of Fig. 7, taken along the line 8—8.

While the invention has been shown and described herein as having been embodied in two and three section sliding sash windows glazed in a particular manner, it is not my desire or intent to thereby unnecessarily restrict the scope or utility of the improvement.

Referring to Figs. 1 to 6, inclusive, the typical two sash window structure shown therein, comprises in general, a fixed frame having an inclined lower sill 10, opposite side jambs 11, a head jamb 12, blind stops 13, and an outside casing 14; and a pair of relatively horizontally adjustable inner and outer sash sections 15, 16 respectively which are slidably supported on lower and

upper horizontal guide bars 17, 18, and each having a bottom rail 19, a top rail 20, an upright check rail 21, and a side rail 22, the latter being cooperable with upright sealing strips 23 secured to the side jambs 11.

The lower sill 10 may be fixedly supported upon the usual bottom lug 24 as shown in Fig. 1, and may also be provided with a cut-out 25 which cooperates with the outside casing 14 to receive the usual screen, blinds, or storm-sash, not shown. The sill 10 may also be provided with angular recesses 26 for properly positioning the lower guide bars 17 and the sill parting stop 27, and for retaining these bars and the stop 27 in parallel position, and the parting stop 27 is secured to the sill midway between the bars 17. The bars 17 and the stop 27 extend from one side jamb 11 to the other, and may be provided with weep holes 28 as shown in Figs. 1 and 2, which effectively cooperate with the recesses 26 to permit free escape of moisture. A stool 29 of usual construction may also be secured to the upper inner edge of the sill 10 as shown in Fig. 2, and the bottom rails 19 of the sash sections 15, 16 are provided with lower grooves 30 which slidably engage the lower guide bars 17.

The opposite side jambs 11 of the window frame, are rabbeted or grooved to receive side parting stops 31 which extend upwardly from the opposite ends of the lower stop 27 to the top of the opening, and the upright sealing strips 23 coact with grooves 32 formed in the jambs 11 on opposite sides of the parting stops 27, 31 as shown in Figs. 4 and 5. Each of the sealing strips 23 is preferably provided with an outer chamfer or inclined surface 33 which is cooperable with a vertical groove 34 formed in the side rail 22 of the corresponding sash section 15, 16 as illustrated in Figs. 4 and 5; so that when the inner sash 15 is closed, its outer surfaces will be forced by the chamfer into snug engagement with the parting stops, and when the outer sash 16 is moved toward closed position, its outer surfaces will likewise be forced by the surface 33 of its sealing strip 23 into snug coaction with the blind stops 13.

The head jamb 12 of the two sash frame, is also rabbeted for the reception of an upper parting stop 35 as shown in Fig. 3, and the upper parallel guide bars 18 which coact with grooves 36 formed in the top rails 20 of the sash sections 15, 16, may also be confined in grooves 37 formed in the head jamb 12. The upper guide bars 18 and parting stop 35 also extend throughout the entire width of the window opening. The main frame of the window may also be provided with an outer drip cap 38, and with inner adjustable casing stops 39, and the head jamb 12 may be caused to coact with an upper lug 40 in the usual manner.

The inner and outer horizontally slidable sash or sash sections 15, 16 may be provided with glazing or glass 41 of any desired type, and the check rails 21 of the sash are adapted to snugly coact along inclined surfaces as shown in Fig. 6. The check rails 21 are provided with the usual cam lock or latch 42 operable from the inside of the window, to force the check rails into sealing engagement with each other and to simultaneously force the sections 15, 16 against the side jambs 11 and into sealing engagement with the stops 31, 13, respectively. The bottom and top rails 19, 20 of the two sash sections 15, 16 are preferably formed to extend throughout the entire width of each sash, so as to prevent relative

sliding of elements along grains extending transversely of each other, and it is to be noted that with the exception of the latch 42, glazing 41 and nails which may be used in assembling parts,

5 the entire window structure may be formed of wood. The guide bars 17, 18 and sealing strips 23 are preferably formed of hard wood or other fibrous material or composition; and in order to enhance the sliding action, these bars may be lubricated by saturation with oil or paraffin or otherwise.

The improved modified window structure of Figs. 7 and 8 is similar in construction to that shown in Figs. 1 to 6, inclusive, except that the blind stops 13 and the parting stops 27, 31, 35 have been omitted, and the assemblage is provided with three sash sections instead of only two. Referring to Figs. 7 and 8, the window specifically shown therein comprises a main frame having a lower sill 10, opposite side jambs 11, a head jamb 12, and outer and inner casings 14, 14'; and three relatively horizontally adjustable inner and outer sash sections 15, 16 respectively which are slidably supported on lower and upper horizontal guide bars 17, 18, and each having a bottom rail 19, and a top rail 20. The outer medial sash section 16 is provided with upright check rails 21' at its opposite sides which are cooperable with vertical check rails 21 of the two inner sash sections 15, and each of these inner sections 15 has a side rail 22 which is co-operable with an upright sealing strip 23 secured to the adjacent side jamb 11 of the frame. Each of the side jambs 11 is also provided with an upright recess 43 disposed in alignment with the inner guide bars 17, 18, and the sash sections 15, 16 should again be provided with locking latches 42 at their cooperating check rails 21, 21'. The glazing 41 of this modified three sash window assemblage, may again assume any desired form, and the structure is likewise formed of wood with the horizontal bottom and top rails 19, 20 of the sash sections 15, 16 extending throughout the entire width of these sections.

45 Either of the multiple sash horizontally slid-
able window structures shown may be built with
two or more inner and outer sash sections 15, 16;
and when three sash are utilized, the mid-section
50 may be placed either on the inside or outside, and
this mid-section may also be fixedly mounted if
so desired. When in normal use, the sash sections
15, 16 can be slid horizontally relative to
55 each other upon release of the latch or latches
42, to provide elongated vertical ventilating open-
ings equal to the full height of the window open-
ing and of any desired width within the space
provided. With the two sash window, the sash sections 15, 16 may be superimposed upon each
60 other to provide a ventilating opening approxi-
mately equal to the area of one sash adjoining
either side jamb 11; and with the three section
65 window assemblage such an opening may also be
provided adjacent to either side jamb. By omit-
ting the inclined surfaces of coaction between the
check rails 21, 21' of the three section window,
70 the mid-section 16 may also be shifted from side
to side, thus providing an extremely flexible ar-
rangement. When the windows are closed and
the locking latches 42 are operated to seal the
75 sash, the outer surfaces of the rails of the sash sections 15 will be driven into sealing engage-
ment with the adjacent stop surfaces of the
frame, by the inclined surfaces 33 of the sealing
strips 23, and the window will be tightly sealed
without the aid of special metallic sealing strips.

During opening and closing of the windows, the sash sections 15, 16 slide along the horizontal guide bars 17, 18 and the formation of the bottom and top rails 19, 20 with the grain thereof extending throughout the width of each sash section 15, 16 and substantially parallel to that of the guide bars 17, 18 insures easy sliding at all times. Whenever the sliding motion of any section 15, 16 is arrested, the sash will remain in the adjusted position without the aid of sash balances of any kind, and the openings 26 in the lower bars 17 and in the lower parting stop 27 will insure proper drainage of liquid from the lower sill 11 at all times.

From the foregoing detailed description it will be apparent that my present invention provides an improved window structure which is extremely simple, compact and durable in construction, and which is moreover highly efficient and flexible in its adaptations. The improved window assemblies are devoid of unnecessary metallic parts, and require no special or metallic weather sealing strips or sash counter-balances of any kind. The guide bars 17, 18 and the side sealing strips 23 perform the function of weather strips, and by virtue of the upright disposition of the check rails 21, 21', the sash sections 15, 16 will be retained in various positions of adjustment by gravity. The vertical elongation of the horizontally slidable sash sections 15, 16 also provides for better ventilation by producing vertically elongated openings, and the sections 15, 16 are easily operable since they do not require physical lifting. The improved windows can be manufactured in various sizes and shapes at moderate cost, from readily available stock materials, and are devoid of outwardly or inwardly projecting parts when the sash sections are open and when closed.

It should be understood that it is not desired to limit the present invention to the exact details of construction and operation herein shown and described, for various modifications within the scope of the appended claims may occur to persons skilled in the art.

I claim:

1. A sliding sash window, comprising, a main rectangular window frame having parallel intermediate and inner stops, a set of elongated horizontal upper and lower guide strips spanning said frame between the inner and intermediate stops and outwardly of the intermediate stops, upright wedge strips secured to each side jamb of said frame in vertical alinement with the guide strips of each set, each of said wedge strips having a wedge surface facing inwardly of the window opening, and a sash section slidable horizontally along each set of said upper and lower guide strips, said sash sections having cooperating check rails and also having vertical wedge grooves in their side rails remote from said check rails and cooperable with said wedge strips to force the sash rails against said stops when the sash sections are moved to closed position.
2. A sliding sash window, comprising, a main rectangular window frame having parallel intermediate and inner stops, a set of elongated horizontal upper and lower guide strips spanning said frame between the inner and intermediate stops and outwardly of the intermediate stops, upright wedge strips secured to each side jamb of said frame in vertical alinement with the guide strips of each set, each of said wedge strips having a wedge surface facing inwardly of the window opening, a sash section slidable horizontally along each set of said upper and lower guide strips, said sash sections having cooperating check rails and also having vertical wedge grooves in their side rails remote from said check rails and cooperable with said wedge strips to force the sash rails against said stops when the sash sections are moved to closed position, and a latch associated with said cooperating check rails for simultaneously forcing said sash sections against their corresponding wedge strips during closing and sealing of the window.

OTTO H. MERZ.
